UNITED STATES PATENT OFFICE.

LLOYD R. RHEIN, OF DETROIT, MICHIGAN, ASSIGNOR TO C. R. WILSON BODY COMPANY,
OF DETROIT, MICHIGAN, A CORPORATION OF MICHIGAN.

VEHICLE DOOR LOCK.

Application filed August 19, 1920. Serial No. 404,574.

To all whom it may concern:

Be it known that I, LLOYD R. RHEIN, a citizen of the United States of America, residing at Detroit, in the county of Wayne and State of Michigan, have invented certain new and useful Improvements in Vehicle Door Locks, of which the following is a specification, reference being had therein to the accompanying drawings.

10 This invention relates to vehicle door locks and more particularly to locks for the doors of vehicles of a closed body type.

It is one of the objects of the invention to provide a vehicle door lock having an interior auxiliary control means which may be adjusted by an occupant of the car to insure locking when the car is closed after the occupant has stepped out, a key being required only to effect unlocking when it is desired to again enter the vehicle.

15 It is a further object of the invention to provide a device interiorly of a door for locking the door against operation by the outside handle without interfering with control of the bolt by the inside handle.

The invention consists in the structural features and arrangements of parts herein-after fully described and illustrated in the accompanying drawings, wherein:

20 Figure 1 is an exterior view of a door to which the approved lock is applied;

Figure 2 is an interior view of the same;

25 Figure 3 is a fragmentary exterior view of the door with a portion broken away to show the release of the inside locking device through application of a key to the outside lock;

Figure 4 is a section on line 4—4 of Figure 1.

30 In these views the reference character A designates an automobile door and B the supporting plate of a lock for said door, said plate being mounted flush with the inner face of the door. C is a bolt slidably mounted upon the plate B and having at one extremity the bolt head C' engaging a face plate D formed as a flange on one end of plate B. Said bolt is adapted to be retracted interiorly of the door A by a handle

35 E pivoted at F upon the lower portion of the plate B and projecting upwardly above the door, an intermediate portion of said member E being engageable with an arm G upstanding on the bolt C in the plane of said member. Normally the bolt is retained

in its projected position by a coiled spring H. As a provision for retracting the bolt C from the car exterior, there is provided upon the outside of the door A a rotative handle I carried by a stem I'. Adjacent the plate B said stem carries a cam J which is engageable with a second upstanding arm K upon the bolt C to retract said bolt upon a counter clockwise rotation of the handle I. Upon the exterior face of the plate B there is mounted a U-shaped bracket L which forms a slide bearing for a rotative plunger M having an actuating knob N on its outer end and carrying adjacent the inner face of the plate B a U-shaped locking member O. The member O projects into a bracket O' mounted upon the face plate D and carries a leaf spring Q bearing at its free end upon the upper portion of said bracket and forcing the locking member O against a stop O² formed by the lower portion of said bracket. R indicates an ordinary type of lock which is set into the exterior face of the door A, and which, when engaged by a suitable key S is adapted to rotatably actuate a squared stem T universally jointed to said lock and having its inner end engagement in a square orifice U in the member O.

Considering now the operation of the described construction, when the plunger M is retracted the member O is engaged with a shoulder V formed upon the cam J, and the handle I which is connected thereto will thus be restrained against the counter-clockwise rotation requisite to effect retraction of the bolt C. When however, said plunger M is projected, the member O is shifted out of engagement with the shoulder V and the bolt C may then be retracted by the handle I. When the occupant of a car equipped with the described lock is about to leave the car and desires to lock the door, the plunger M is retracted by means of its knob N. Thus the exterior handle I is locked against rotation, yet the bolt is free for actuation by the handle E and may undergo the momentary retraction necessary to closing of the door after the occupant has stepped out of the vehicle. When it is again desired to enter the vehicle, the key S is applied to the lock R and is actuated to turn the stem T in a counter-clockwise direction. Owing to engagement of the stem T in the squared orifice U of the locking member O, said member participates in the counter-clockwise rotation

2
of the stem and is thus shifted clear of the shoulder V of the cam J. While the locking member is held thus rotatably displaced by means of the key S, the handle I is turned to 5 retract the bolt C and the door is then opened.

The described device saves the driver of a closed car the trouble and annoyance of fitting a key to the lock of a door whenever 10 the latter is left alone, use of the key being required only to reenter the car. It is an important feature of the described invention that an application of the auxiliary interior locking device comprised by the elements M, N and O does not deadlock the bolt 15 and has no effect on control of the bolt by the interior handle member E. Thus, the occupant of the car may, if desired, retract the plunger to effect locking of the outer handle 20 member before the door has been opened, the handle E being then actuated to open the door and afford egress to the occupant.

What I claim as my invention is:

1. In a vehicle door lock, the combination 25 with a bolt and means normally projecting the same, of interior means for retracting

the bolt, exterior means for retracting the bolt, including a cam engageable with the bolt and provided with a locking shoulder, a locking member movable both rotatively and rectilinearly into or out of engagement with said locking shoulder, means located interiorly of the door for rectilinearly actuating said locking member into engagement with said locking shoulder, and key operable 30 means located exteriorly of the door and rotatively actuating said locking member out of such engagement.

2. In a vehicle door lock, the combination 40 with a bolt and means normally projecting the same, of interior means for retracting the bolt, exterior means for retracting the bolt, a locking member controlling said exterior means and movable both rotatively and rectilinearly to effect such control, means located interiorly of the door for rectilinearly actuating said locking member, and a key operable means located exteriorly of the door 45 for rotatively actuating said locking member.

In testimony whereof I affix my signature. 50

LLOYD R. RIEIN.
